UNITED STATES PATENT OFFICE

102,976

DESIGN FOR A VAPORIZER

Samuel Rosenblatt, Chicago, Ill.

Application December 2, 1936, Serial No. 66,268

Term of patent 7 years

To all whom it may concern:

Be it known that I, Samuel Rosenblatt, a citizen of the United States, residing at Chicago, in the county of Cook and State of Illinois, have invented a new, original, and ornamental Design for a Vaporizer, of which the following is a specification, reference being had to the accompanying drawing, forming a part thereof.

In the drawing:

I claim:

The ornamental design for a vaporizer substantially as shown.

SAMUEL ROSENBLATT.
